UNITED STATES PATENT OFFICE

JOHN CONDELL, OF NEW YORK, N. Y.

SHOE.

SPECIFICATION forming part of Letters Patent No. 380,552, dated April 3, 1888.

Application filed November 22, 1887. Serial No. 255,908. (No model.)

To all whom it may concern:

Be it known that I, JOHN CONDELL, a citizen of the United States, residing at New York, in the county of New York and State of New York, have invented new and useful Improvements in the Manufacture of Boots and Shoes, of which the following is a specification.

My invention relates to the manufacture of boots and shoes, and the purpose thereof is to provide a shoe in which the weight of the wearer shall be equally distributed, the natural form of the foot preserved, and the leather of the upper supported in its normal position, whereby greater ease as well as superior wearing qualities are secured, while the shape, approximating closely to that of the natural foot, when well formed is much more graceful.

It is also my purpose to provide a construction whereby the outer sole is secured to the insole in such manner as to permit the former to have close bearing upon the upper, forming a tight joint between the parts, and thereby avoid the channel or space usually formed in shoes above the edge of the outer sole, and in which mud and water are extremely liable to lodge. It is a further advantage of this construction that I am able to use a narrower sole and to form the edges thereof with a bevel or flare from the bottom upward, while the foot portion or upper overhangs or projects beyond the sole, thereby throwing the splash away from the foot.

It is a further purpose of my invention to provide an improved form of upper, having such a shape that it may be lasted without the severest stretching and tension usually employed to draw the edges down upon the heel, whereby the leather is wrinkled at the instep and ball of the foot and more or less deformity of the finished shoe always produced.

It is my purpose also to provide a shoe in which the necessity of a steel shank to retain the arch of the instep shall be wholly avoided, the leather being retained in proper form and position by the weight of the wearer, in conjunction with the novel construction by which the weight is utilized for this purpose.

My invention also contemplates an improved method of connecting the outer sole, insole, and upper by a single stitching, whereby the

channeling of the face of the outer sole to receive the thread is avoided and the wear and appearance of the shoe are greatly improved. Finally, I propose to utilize the grained surface of the outer sole to give strength and long wear to the stitching.

To these ends my invention consists in the several novel features of construction and new combinations of parts hereinafter fully set forth, and definitely pointed out in the claims.

In the accompanying drawings, Figure 1 is a diagram showing the form of the upper ready for the last, the dotted lines showing the old form heretofore used. Fig. 2 is a side elevation of a shoe constructed according to my invention. Fig. 3 is a transverse section of Fig. 2 on the line 3 3, the scale of drawing being somewhat enlarged. Fig. 4 is a side elevation of a man's shoe constructed in accordance with my invention. Fig. 5 is a partial longitudinal section of Fig. 4. Fig. 6 is a bottom plan view of the heel.

In the said drawings, the reference-numeral 1 denotes the upper, which I cut, as shown in full lines in Fig. 1, the ankle portion 1^a inclining backward and the heel portion 1^b being extended downward, so that the margin shall substantially coincide with the outline of the last. When thus formed, the upper can be lasted with great ease and made to conform to the shape of the last without wrinkling or drawing out of shape.

The numerals 2 and 3 designate, respectively, the insole and the outer sole, the insole being shaped between metallic forms which approximate the natural convexities of the human foot, thereby producing a margin, 4, which lies closely against the rounded edge of the foot and supports the leather in true and natural position. The upper 1 is lasted upon the insole in any suitable manner, and the outer sole being secured in place the three are united by a single continuous line of stitching, 5.

Preparatory to stitching a crease or channel, 6, is formed in the edge of the outer sole, and preferably nearer to the inner than to the outer edge, the strength of material being such as to permit two-thirds of the thickness of the outer sole to lie below the channel, and therefore add this greatly-increased protection.

to the seam. The stitching is then carried along this channel and through the insole, which may be creased, if desired.

It should be noted that I turn the grained surface 3^a of the outer sole inward, so that it lies against the outer surface of the insole. I thus avail myself of the greatly superior strength, tenacity, and toughness of this surface to support the seam, and I am thereby enabled to attach the outer sole with great strength and permanence by stitching through one-third of its thickness only. I employ no metallic shank in this shoe, but so construct and apply the heel that it gives the proper support to the instep and preserves the arch thereof.

The construction being essentially the same in both ladies' shoes and those worn by men, I will describe it in connection with Figs. 4 and 5.

The heel 7 is formed of leather or any suitable material, and is provided with a forwardly-projecting tongue, 8, which underlies that portion of the heel. Upon its "tread" 9 the surface is convex from front to rear, and the height of the heel is greatest at the forward point and is lowered slightly toward the rear. The weight of the wearer will tend to depress the rearward part of the heel, rocking it slightly upon the convex tread 9, and this movement will slightly raise the tongue 8 and arch the instep portion of the sole, as clearly indicated by the dotted lines in Fig. 5. This feature of construction, moreover, produces a more agreeable action in walking, as the curve or convexity of the tread of the heel approximates the natural motion of the foot in walking, making less noise and producing less fatigue.

By my method of uniting the outer sole by channeling the edge thereof and laying the seam in said channel I am not only able to make a tight joint between the upper and the edge of the outer sole, thereby preventing mud and filth from lodging between them, but I can also diminish the width of the outer sole and give it a slight bevel or flare from the outside upward. This form, in conjunction with the outwardly-projecting or overhanging border of the inner sole and upper, will naturally operate to divert splashes outward away from the foot.

It will be seen that by my invention I unite the outer sole and inner sole without using either welt or filling, which is an advantage that will be appreciated by those skilled in the art.

What I claim is—

1. The upper for boots and shoes herein shown and described, having the ankle portion 1^a inclined toward the rear to overhang the 60 end of the heel and provided with a downwardly-extended heel portion, 1^b, which overlaps the heel of the last without stretching, substantially as set forth.

2. In the manufacture of boots and shoes, an 65 outer sole having a channel or crease formed in its edge to receive the seam uniting the insole, outer sole, and upper, substantially as described.

3. In the manufacture of boots and shoes, 70 the combination, with an upper and an insole, of an outer sole having a channel formed in its edge, and a line of stitching laid in said channel and passing through the grained surface of the outer sole through the upper and through 75 the insole, substantially as described.

4. The combination, with a boot or shoe, of a heel having a forwardly-projecting tongue which underlies part of the arch of the instep, said heel having the highest portion of its 80 tread at the forward part thereof, substantially as described.

5. The combination, with a boot or shoe, of a heel having a tongue or projection which partly underlies the arch of the instep, said heel having 85 a tread which is convex from front to rear, the forward portion being the higher, substantially as described.

6. A shoe having the upper and sole united by stitching which enters the edge of the sole 90 and passes obliquely inward through the upper, which lies upon the sole, and through the edge of the insole, which overlies the edges of the upper, the grained surface of the sole being laid next the foot, substantially as de- 95 scribed.

7. A shoe having the sole, insole, and upper united by stitching passing obliquely from the edge of the sole through the superposed upper and provided with a heel having a tongue projecting forward under the instep portion, said heel being higher at the forward than at the rear portion, substantially as described. 100

In testimony whereof I affix my signature in presence of two witnesses.

JOHN CONDELL.
